SHIRT HOLDER

Carl Otto Leonard Mannervik, Oskarshamn,
Sweden

Application May 23, 1946, Serial No. 671,788
In Sweden December 6, 1945

4 Claims. (Cl. 223—71)

1

The present invention refers to shirt holders in the form of a piece of sheet material to be thrust into a shirt to keep it settled in stock or for display and having a foldable flap member secured thereto and adapted to bear on the lower portion of the shirt, which is to be folded rearwardly and upwardly about said frame member toward the neck-band or collar of the shirt.

The invention is principally distinguished by the combined features that the folding or crease line of the flap member on the frame member is located at a distance underneath the upper edge of the frame member, that the upper edge of the frame member has a projection adapted to enter the neck-band or collar of the shirt to form a support for said neck-band or collar and that stay strips are provided within the border of the frame over which the sleeves are folded.

The invention will be described more closely hereinafter with reference to a few forms of embodiment illustrated by way of example in the accompanying drawings.

Fig. 1 is a plan view of a shirt holder embodying the invention, and Figs. 2-5 are plan views showing the holder and a shirt in the different stages of the folding of the shirt on the holder.

In the form of embodiment illustrated in Figs. 1-5, 4b designates the frame member proper, which may be made from paste-board, carton or the like. An opening 25 is provided in the frame member by three incisions. Extending from the upper uncut side is the flap 5c which at its securing edge is preferably provided with a crease line so as to permit of being folded conveniently from the plane of the frame member 4b. Furthermore, there are sleeve holding strip members 21 and 22 cut out along the sides of the flap 5c, said strip members being attached to the frame member 4b, one 22, of the strip members having preferably a crease line 3a so as to permit of being readily folded out from the plane of the frame member 4b, while the other strip member 21 may be without such a crease line. At or near its lower edge, the flap 5c shows projecting clamping members 26 intended to grip about the sides of the frame member and the shirt.

In the securing of the shirt 27, one proceeds so that the holder is placed upon the shirt which is spread out with the back side thereof turned upwardly, the portion 6 being thrust underneath the collar. After that, the flap 5c and the strip member 22 are folded up into the position shown in Fig. 2. The one (right hand) side of the shirt is then folded about the long edge of the holder, the appurtenant sleeve 23 being stretched and

taken underneath the strip member 21 and then back over the same, whereupon it is pressed into ordinary folds, the cuff portion being taken over the edge of the frame member to the front side.

5 After that, the other (left hand) side of the shirt is folded about the corresponding edge of the frame member in the manner shown in Fig. 3. The appertaining sleeve 24 is stretched, and the strip member 22 is folded down, whereupon the 10 sleeve is folded about the strip member 22 and back, the same being then pressed in the ordinary manner, with the cuff portion folded over, to the front side of the shirt, as shown in Fig. 4. The lower portion of the shirt is then folded upwardly toward the neck-band, whereupon the 15 flap 5c is folded down into the position shown in Fig. 5. The clamping members 26 are taken about the side edges of the packed shirt and clamped or secured in their positions in any 20 suitable manner.

What I claim is:

1. A shirt holder comprising, in combination, a substantially rectangular frame member consisting of a piece of sheet material to be thrust 25 into a shirt to keep it settled in stock or for display, a projection on the upper end of said frame member adapted to enter the neck-band or collar of the shirt to form a support for said neck-band or collar, an elongated central flap member hinged at one end on said frame member below the upper edge thereof, and sleeve holding strip members located within the boundary of said frame member and laterally of said central flap member, said strip members being connected at 30 one end to said frame member and adapted to support the sleeves of the shirt in the folding of the same on the shirt holder.

2. A shirt holder comprising, in combination, a substantially rectangular frame member consisting of a piece of sheet material to be thrust 35 into a shirt to keep it settled in stock or for display, a projection on the upper end of said frame member adapted to enter the neck-band or collar of the shirt to form a support for said neck-band or collar, an elongated central flap member hinged at one end on said frame member below the upper edge thereof, and strip members cut out from the material within the boundary of said frame member flanking said central 40 flap member, said strip members being connected at one end to said frame member and adapted to support the sleeves of the shirt in the folding of the same on the shirt holder.

3. A shirt holder comprising, in combination, 45 a substantially rectangular frame member con-

sisting of a piece of sheet material to be thrust into a shirt to keep it settled in stock or for display, a projection on the upper end of said frame member adapted to enter the neck-band or collar of the shirt to form a support for said neck-band or collar, an elongated central flap member hinged at one end on said frame member below the upper edge thereof, and strip members cut out from the material within the boundary of said frame member flanking said central flap member and connected at one end to said frame to support the sleeves of the shirt in the folding of the same on the shirt holder, said central flap member and said strip members extending from the same end portion of said frame member.

4. A shirt holder as claimed in claim 3, wherein both of said strip members have a crease line adjacent the point of connection thereof to the frame to facilitate their folding out from said frame member.
